CLAIM

We claim the ornamental design for a modular display, as shown and described.

DESCRIPTION

FIG. 1 is a front perspective view of a modular display showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depicting portions of the modular display form no part of the claimed design.

The grayscale tones shown in the drawing figures are intended to illustrate color contrast, and not any particular shade or tone of color.
